[57] CLAIM

The ornamental design for a toy play scene, substantially as shown and described.

DESCRIPTION

FIG. 1 is a perspective view of a toy play scene showing my new design;

FIG. 2 is a perspective view thereof, showing the side and end opposite to those shown in FIG. 1;

FIG. 3 is an elevational view taken from one end thereof;

FIG. 4 is an elevational view thereof, taken from the end opposite that shown in FIG. 3; and,

FIG. 5 is a top plan view thereof.

FIG. 1

FIG. 2

FIG. 3

FIG. 4

FIG. 5
